UNITED STATES PATENT OFFICE.

RAOUL J. GRUENBERG, OF SAN FRANCISCO, CALIFORNIA.

BOX-COLLAPSING MACHINE.

Application filed January 2, 1923. Serial No. 610,400.

To all whom it may concern:

Be it known that I, RAOUL J. GRUENBERG, a citizen of the United States, residing at San Francisco, in the county of San Francisco, State of California, have invented a new and useful Box-Collapsing Machine, of which the following is a specification in such full and clear terms as will enable those skilled in the art to construct and use the same.

This invention relates to a box collapsing machine, and its object is to provide means whereby certain types of folding boxes may be completely collapsed and flattened for shipment.

It will be understood by those skilled in the art, that egg boxes and certain other types of boxes are delivered in considerable quantities from the machine which sets them up and glues them. These boxes must then be collapsed along the creasing lines formed on them flattened and then placed in bundles for shipment, and since such boxes are sold very cheap the work must be accomplished by an automatic machine capable of running about 80 boxes per minute to keep up with the gluing machine.

Another object of the invention is to produce a machine which will be capable of taking different sizes of boxes, the smallest size being known as the 3 by 4 and the largest as the 2 by 6, although both sizes hold one dozen eggs.

Another object of the invention is to provide a simpler construction of the folding in which the box will not be pressed against a stop plate and detained during the period of folding, but in which the box will be continuously moving through the collapsing apparatus, thereby increasing the capacity of the machine.

Other objects of the invention will appear as the description proceeds.

An embodiment of the invention is shown in the accompanying drawings, in which the same reference numeral is applied to the same portion throughout, but I am aware that there may be modifications thereof.

Fig. 1 is a plan view of the complete machine,

Fig. 1^a is a side elevation of one of the angles for holding the belt supporting floor,

Fig. 2 is a side elevation of the complete machine,

Fig. 3 is an end elevation of the machine 55 looking from the left, Fig. 1,

Fig. 4 is an end elevation of the complete machine looking from the right, Fig. 1,

Fig. 5 is a view of the folding plates on a larger scale than the other figures, to show 60 the method of adjustment thereof, the supporting belts being shown in section, and

Fig. 6 is a diagrammatic side elevation of a modified form of the invention in which there is a mechanism to turn the boxes to 65 the proper folding position, said turning device being necessary on some forms of setting up machines.

The frame of the machine comprises four vertical posts 1 to 4 inclusive, connected by 70 two longitudinal bars 5 and 6, and by two cross bars 7 and 8.

Connecting the two cross bars 7 and 8 are two flat supporting boards 9 and 10 for the two belts 11 and 12. These two boards 75 form the floor for the two belts to run over and they are held in place by four cast iron angle plates 13, two of which on the board 10 are shown in Figure 2. These angles have two holes 14, 15 to receive two bolts 16 80 which connect the angles to the boards 10 and 11, and a slot 17 through which the bolts 18 pass to secure the angles to the cross bars 7 and 8. The object of the slot 17 is to provide means whereby the position of the 85 boards may be easily adjusted to enable the machine to take boxes of different lengths. Secured on the edges of the boards 9 and 10 are two stationary cams 21, 22, which cams are slotted to enable them to be adjusted to 90 operate the folding plates later to be described at a different place in the belt travel to operate on boxes of different sizes. The cams are held in place by bolts 23, 24, passing into the belt supports 9 and 10. 95

Supported independently of said cams near them at each side of the machine are two L-shaped arms 25 which have bosses 25', and each boss has a tube 26 extending therefrom through which the rods 27 slide. 100

Each rod 27 has a head 28 which is held against the end of the tube 26 by a coiled spring 29, and a small roller 30 is placed on the end of the rod to contact with the box ends to collapse them. The rods 27 are 105 square so they cannot rotate as they are pushed forward. The heads 28 each have a depending pin 31 so placed as to contact

with the cams 33, 34 placed on the edges of the belts 9 and 10 respectively. The position of these pushers remains fixed with respect to the length of the belts regardless of the other adjustments.

The belts 11 and 12 run over four pulleys 35, 38 inclusive on two shafts 39, 40 journaled in two slideable bearings 41, 42 and two fixed bearings 43, 44. Set screws 45 to 48 inclusive in the several pulley hubs enable the position of the pulley to be changed for boxes of different lengths. The belts 9 and 10 have a folding mechanism for the box side consisting of two plates 49, 50, mounted on a rod 51 and tube 52 respectively, with the rod extending into the tube for a greater distance than the full width of the belt 9. The rod has a depending arm 53, and the tube a similar depending arm 54, the object of which is to contact with the cams 21, 22 and press the plates 49, 50 down on the box side. The rod 51 and tube 52 are pivotally mounted in four small bearings 56 to 59 on the belts 9 and 10. The machine shown has two sets of folding plates 49, 50 and two sets of cams 33, 34, as will be seen on the under-side of the belts in Figures 2 to 4, so two boxes are folded with each complete turn of the belts. The number of folding mechanisms in any given machine will depend on the work the machine is called on to do, but may be increased if desired.

The bearings 41, 42 are slideable in two yokes 60, 61, secured to the posts 1 and 2, and said bearings may be adjusted in position to tighten the belts by turning up the screws 62, 63.

Over the belts 9 and 10 are two rollers 64, 65, adjustably mounted on a shaft 66, journaled in the bearings 67, 68. The bearings 67, 68 are secured on the posts 1 and 2 in such a position as to bring the rolls 64, 65 close to the top of the belts 9 and 10.

The machine is driven by the pulley 69 on the shaft 39 which shaft also carries a small grooved pulley 70 around which a crossed belt 71 passes to the pulley 72 on the shaft 66. An arm 73 pivoted on the side of the post 2 has a tightener pulley 74 bearing on the crossed belt 71. This tightener pulley is held against the belt by means of a screw 76 passing through an arm 75 on the post 2.

The operation of the folder is as follows:

Assuming a suitable feeding machine to place the boxes on the belts in the position shown in Figures 1 and 2, the belt will carry it along until it touches the rollers 64, 65 whereupon if the folding plates do not happen to be at hand the box will be detained until the folding plates catch up with the box, at which moment the arms 53, 54 will strike the cams 21 and 22 and cause the plates to press on the front side of the

box the rollers 64, 65 holding the box back enough for the folding plates to act on it, but at the same time allowing it to pass ahead at the same speed as the belt is traveling. At the same moment the cams 33, 34 are pushing the small rollers 30 against the box from both ends thereby perfecting the fold along the forward edge of the box. It will be noted that the cams 33, 34 advance the rollers 30 at substantially the same rate of travel of the belts so they follow the box creases closely. During this same time the box is being pushed under the rollers 64, 65 and when it leaves those rollers the folding plate operating arms 53, 54 have left the cams 21, 22 and the box is free to drop off the end of the belt into any suitable receptacle, and because of the pressure exerted on it by the apparatus it will remain flat enough for convenient packaging in bundles of 50 or 100 as desired.

The machine is adjusted for larger boxes by separating the belts slightly and at the same time separating the belt supports to correspond. If a wider box is to be used the cams 21, 22 are set to the right, Figures 1 and 2, more than they are now shown, whereby the folding plates will be pressed down at a greater distance from the flattening roll than as at present shown.

It is to be noted that as soon as the cams 33, 34 pass the pins 31 that the rollers 30 will be snapped back out of engagement with the box leaving it free to be completely flattened. It will also be noticed that the arms 53, 54 do not leave the cams 21, 22 until the box is far enough under the rollers 64, 65 to prevent the plates from rising, as they will do normally because of the weight of the arms 53, 54, which are made heavy enough to accomplish this object.

Since some setting up machines deliver the boxes in a particular way it may be advisable in some cases to turn the belts to the position shown in Figure 6, the machine being otherwise substantially the same. In this figure one of the belts carrying the folding plates is shown at 80 passing over the floor 81. This floor has the cam 82 secured on its edge, and the fixed end folder arm 83 secured adjacent said cam. The two belts pass over pulleys 84, 85. The belts carry the folding plate 86 operated by the arm 87 substantially the same as in the previous form of the invention. The belt is placed at an incline of about forty five degrees to receive the boxes on their bottoms, as they slide down another belt 88 extending at right angles to the first belt, and moving at substantially the same speed as the first belt. The boxes drop on the belt 88 from the gluing machine, as indicated in dotted lines and a gate 89 pivoted on the frame 90 turns the boxes over do they assume the proper

position to land bottom down on the belt 80. The belt 88 passes around two pulleys 91, 92, the former of which is close enough to the belt 80 to hold the box down so it can pass under the belt 93 on the pulleys 94, 95 to be completely flattened, the roller 95 being held down on the belt 80 with such force as may be required to flatten the boxes as desired.

5 The rods 51 hold the belts in alignment 10 in addition to the fact that they pass over pulleys of the same size.

What I claim is as follows, but modifications may be made in carrying out the invention shown in the drawings and in the above 15 particularly described form thereof, within the purview of the invention:

1. A box collapsing machine comprising an endless belt, a flattening roller arranged closely over the belt, a flattening plate carried by the belt to collapse one side of the box and push it under the roller, means to press said plate against the box side and spring retracted means for pushing the box ends inwardly.

25 2. A box collapsing machine comprising an endless belt, a flattening roller over the belt, a flattening plate carried by the belt to collapse one side of the box and push it under the roll, means to press said plate against the box side, and means to push the box ends inwardly.

3. A box collapsing machine comprising an endless belt, a flattening roller over the belt, a flattening plate carried by the belt to collapse one side of the box and push it under the roll, a pair of fixed brackets, slideable rods carried by said brackets to collapse the box ends, and means to push the rods against the box ends to collapse them.

40 4. A box collapsing machine comprising a belt, a presser roll thereover, a folding plate on the belt to collapse one side of a box, pushers at the sides of the belt to push the ends of the box in, and means on the belt to operate the pushers when the belt comes to the box collapsing position.

5. A box collapsing machine comprising a carrier, a presser roll thereover, a folding plate on the carrier to collapse one side of the box, cams for operating said plate at a given place in the travel of the carrier and means to collapse the ends of the box inwardly as it is carried under the presser roll.

55 6. A box collapsing machine comprising a carrier, a presser roll thereover, a folding plate on the carrier to collapse one side of the box, cams for operating said plate at a given point in the travel of the carrier and a pair of rollers to push in the box ends as the box passes under the presser roll.

7. A box collapsing machine, comprising a carrier, a folding plate to collapse one side of a box, means to operate said plate at a given point in the travel of the carrier, box

flattening means, and means to collapse the ends of the box as it is passing under the flattening mechanism.

8. A box collapsing machine comprising a double carrier, double plates carried thereby to flatten one side of a box, cams to operate said plates means to adjust the position of the carrier parts to enable the machine to take boxes of different lengths and means to collapse the box ends inwardly as it is moving along.

9. A box collapsing machine, comprising a double carrier, double plates carried thereby to flatten one side of a box, means to adjust the carrier to operate on different length boxes a box flattening roll under which the boxes pass and means to collapse the box ends when the box is passing under the flattening roll.

10. In a box collapsing machine, a carrier, means over the carrier to finally flatten a box, means on the carrier to flatten one side of the box as it is carried to the final flattening means, and means at the sides of the carrier to push the ends of the box inwardly.

11. In a box collapsing machine a double carrier, box flattening means over the carrier, means on the carrier adjustable therewith to flatten different length boxes, fixed means to operate the latter flattening mechanism, stationary pushers to collapse the box ends inwardly, and cams on the carriers to operate said pushers.

12. A carrier, means on the carrier to collapse one side of a box, cams on the frame to operate said side collapsing means, means at the side of the carrier to collapse the ends of the box, means on the carrier to operate the end collapsing means and means over the carrier to completely flatten the box as it is carried along.

13. A box collapsing machine, comprising a carrier, pivoted means on the carrier to collapse one side of the box, slideable bars at the side of the carrier to collapse the ends of the box, and a roller under which the box is carried to be completely flattened.

14. A box collapsing machine, comprising a double carrier, an adjustable box-side collapsing mechanism on the carrier, means at the sides of the carrier to push the ends of a box inwardly, and an adjustable double roller under which the carrier takes the box to completely flatten it.

15. A box collapsing machine, comprising a carrier, double plates on the carrier to collapse one side of the box, spring retracted movable bars at the edges of the carrier to collapse the box ends, and a roller under which the carrier takes the box to be completely flattened.

16. A double carrier, means to adjust the position of the parts of the carrier, adjustable box-side folding mechanism supported thereby, means to fold the opposite ends of

the box inwardly, and a roll under which the box is taken by the carrier to completely flatten it.

17. An endless carrier, folding plates pivotally mounted thereon to collapse one side of the box, movable bars at the sides of the carrier to collapse the two ends of the box inwardly, means on the carrier to operate said bars at a given point in the travel of the carrier, and a roller under which the carrier takes the box to completely flatten it.

18. A box folding machine, comprising an endless carrier, a pivoted box side folding plate supported thereon, adjustable slides for collapsing the ends of the box inwardly, means on the carrier to operate said slides, and a flattening mechanism under which the carrier takes the box to completely flatten it.

19. A box folding machine, comprising a carrier, a frame to support the carrier, box side folding plates on the carrier, cams on the frame to operate said plates at a given point in the movement of the carrier, means to collapse the two ends of the box shortly after the first mechanism is operated, and means to completely flatten the box after the sides and ends have been collapsed.

20. A box collapsing machine, comprising

an endless carrier, laterally adjustable plates carried thereby to collapse one side of a box, 30 adjustable cams on the carrier support to operate the folding plates at given point in the travel of the carrier, means at the side of the carrier to collapse the two ends of the box, and a roll under which the carrier takes 35 the box to completely flatten it.

21. A box collapsing machine, comprising a pair of adjustable carriers movable side by side, a pair of plates supported by the carriers adjustable to collapse one side of longer or shorter boxes, means at the sides of the carrier to collapse the two ends of the box inwardly, means on the carrier to operate the latter mechanism, and a roller under which the carrier takes the box to completely flatten it.

22. In a box collapsing machine, a box carrier, means on the carrier to collapse one side of the box, means at the opposite sides of the carrier to collapse the box ends, and means to thereafter completely flatten the box.

In testimony whereof I have hereunto set my hand this 28th day of December, A. D. 1922.

RAOUL J. GRUENBERG.
